METAL THREAD PROTECTOR

Frank J. Kennedy, Mount Lebanon, Pa., assignor, by
mesne assignments, to H. K. Porter Company Inc.,
Pittsburgh, Pa., a corporation of Delaware

Application October 5, 1955, Serial No. 538,600

2 Claims. (Cl. 138—96)

This invention relates to protectors for the threads of pipes, and particularly to thread protectors which are suitable for use on pipes of large size such as are used for oil wells.

Thread protectors of the character indicated are commonly made of steel and they have annular end faces joined to side walls by a curved corner with an inside diameter somewhat greater than the outside diameter of the end of the pipe on which the thread protector is intended to be used. This provides a clearance beyond the mid portion of the side wall to facilitate the threading of the side wall to fit a pipe on which the threads are to be protected. In order to facilitate the placing of the protectors on the pipes, a flaring entrance to the protector is ordinarily provided at the end of the protector opposite the annular end wall.

Such thread protectors are in common use, but they are expensive to manufacture. Another disadvantage has been that unless the thread protectors are screwed on the pipe so tightly that they are difficult to remove, there is danger of the protectors coming unscrewed when the pipes are subject to vibration such as may be encountered during transportation.

It is an object of this invention to provide a thread protector construction which makes possible the manufacture of the thread protector from flat strip stock on automatic, multislide machines. This greatly reduces the cost of the protectors as compared with prior constructions which required extensive, successive forming operations on sections of seamless tubing. With the construction of this invention, all of the operations in making the protector are performed automatically on a multislide machine, except the threading. In order to avoid close manufacturing tolerances, the thread protector of this invention is threaded in a subsequent operation after it comes from the multislide machine in an otherwise completed condition.

Another object of the invention is to provide a thread protector with simple means for exerting a continuous friction force for preventing the connector from becoming unscrewed, and this force does not require that the connector be screwed on the pipe so tightly that it is difficult to remove. With this invention, the force for retaining the connector on the threads continues to operate even though the connector moves to some extent in a direction to unscrew it from the threads. In the preferred construction, the end face of the thread protector has undulations or corrugations at widely spaced and angularly spaced locations around the longitudinal axis of the pipe in position to contact with the end face of the pipe. These undulations are of resilient material which yields to set up a friction force against the end face, and the resilience of the contacting surfaces maintains the friction force even though the thread protector is not screwed on the pipe as tightly as possible, and even though the thread protector moves some in a direction to unscrew it from the pipe.

Another object of the invention is to provide improved means for turning the thread protector on the pipe when screwing it on and when unscrewing it from the pipe. In the preferred construction, notches are provided in the 5 end face of the thread protector for receiving a spanner wrench or a chisel or other tool by which the said protector can be rotated. This is of particular significance in connection with a connector made from a single, curved piece of metal because it locates the forces for turning 10 the thread protector on the face of the protector which functions as a web through which a moment force is transmitted to the side wall of the thread protector with less tendency to break the seam at which the confronting end faces of the thread protector are joined together.

15 Other objects, features and advantages of the invention will appear or be pointed out as the description proceeds.

In the drawing, forming a part hereof, in which like reference characters indicate corresponding parts in all the views;

20 Figure 1 is a side elevation of the thread protector of this invention applied to the end of a pipe;

Figure 2 is a sectional view, partly broken away, and on a substantially larger scale, showing the structure of Figure 1, the section being taken on the line 2—2 of 25 Figure 3; and

Figure 3 is an end view of the structure shown in Figure 2.

Figure 1 shows a thread protector 10 located over the 30 threads on the end of a pipe 11. The thread protector comprises a cap having a side wall 14 and an end wall 15 (Figure 2).

The side wall 14 has a forward portion 18 which includes a rounder corner which is the juncture of the side wall with the end wall 15, and the inside diameter of 35 the thread protector at the forward portion 18 is of larger diameter than the outside diameter of the end of the pipe 11. At the opposite end of the thread protector, there is a flared portion 20 for facilitating the entrance of the pipe 11 into the thread protector. Between the forward portion 18 and the flared portion 20, there is a mid portion 22 with threads on its inside surface for screwing over threads 24 of the pipe 11.

When the thread protector is constructed for use on pipes having tapered threads, as is usually the case, the 40 threads on the mid portion 22 are tapered to fit the threads 24 of the pipe. The purpose of the enlarged inside diameter of the forward portion 18 is to provide a clearance for the holder or end of the tool used for making the thread on the inside surface of the thread protector. The outside diameter of the flared portion 20 is preferably equal to the outside diameter of the forward portion 18. This facilitates the stacking of pipes in parallel relation.

The thread protector 10 is made of a single piece of 45 material, and preferably of resilient metal, such as steel.

In the manufacture of the thread protector, all of the 50 shaping operations are first performed on an automatic, multislide machine, and the material is then bent around a longitudinal axis to bring the opposite ends of the piece together along a seam 28. The confronting faces

60 on opposite sides of this seam are secured together. In the preferred construction, they are connected by a projection 31, on one side of the seam, fitting into a recess 32 on the other side of the seam. The projection and recess are preferably undercut such as the dovetail joint shown in Figure 2. This provides a strong connection with flush surfaces across which the threads can be chased in the same way as if the protector were made of seamless tubing. If desired, the seam can be provided with additional strength by spot welds 36 located beyond the threaded area or on the outside of the thread protector.

65 There are undulations formed by corrugations 38 at 70 the end face of the thread protector. The undulations are formed by a series of angularly spaced locations around the longitudinal axis of the pipe. These undulations are of resilient material which yields to set up a friction force against the end face, and the resilience of the contacting surfaces maintains the friction force even though the thread protector is not screwed on the pipe as tightly as possible, and even though the thread protector moves some in a direction to unscrew it from the pipe.

angularly spaced locations around the longitudinal axis of the thread protector. These corrugations 38 are bent inwardly and they are at locations to contact with the end face of the pipe 11 when the thread protector is screwed on the pipe.

In order to obtain a substantial deflection of the corrugations 38, without requiring excessive force in screwing the thread protector on the pipe, the number of corrugations should be limited. The preferred construction includes only three corrugations 38, and these are located at approximately 120° from one another so that the force for deflecting them is evenly distributed around the pipe. To further facilitate deflection of the metal of the corrugations 38, and to have a greater amplitude of deflection without exceeding the elastic limit of the material, the corrugations 38 should be of substantial width. When the thread protector is made of steel, the corrugations 38 are partially flattened by the pressure against the end face of the pipe and this provides a substantial friction force for preventing the thread protector from becoming unscrewed as the result of vibration. Even if the thread protector turns to some extent in a direction to unscrew it from the pipe, the pressure of the corrugations 38 against the end wall continues to maintain a friction force for preventing further rotation of the thread protector.

The end face 15 has notches 40 for receiving a tool by which the thread protector can be rotated. A spanner wrench can be used, or a chisel, as previously explained. In the construction illustrated, the notches 40 are substantially square recesses in the inside edge of the end face 15, as best shown in Figure 3. The notches 40 are preferably evenly spaced around the axis of the thread protector. Different numbers of notches can be used, but if an even number are used with each notch diametrically opposite from another notch, the construction can be used with simple types of wrenches.

The notches 40 can be of various shapes, but in the preferred construction at least one and preferably both of the sides of the notches 40 extend in directions substantially radial with respect to the longitudinal axis of the thread protector.

The end face 15 preferably extends, throughout most of its area, in a plane normal to the longitudinal axis of the pipe and thread protector. The location of the notches 40 in this inwardly extending end face 15, which is a flange of the thread protector, results in an application of force to the thread protector at a region and in directions which reduce the tendency of the force to break open the portion of the seam 28 along the side wall 14 of the thread protector. Any distortion of that part of the seam 28 could result in a burr along the threads of the mid portion 22, and the provision of the notches 40 for turning the thread protector is, therefore, a protection to the threaded part of the seam 28.

The preferred construction of the invention has been illustrated and described, but changes and modifications can be made, and some features can be used in different combinations, without departing from the invention as defined in the claims.

What is claimed is:

1. In a thread protector of the class wherein a single piece of metal is curved to bring its opposite longitudinal edges adjacent to one another and said edges are connected to form a generally cylindrical wall for surrounding the threads to be protected and in which a flange at one end of the piece of metal curves inwardly and extends across the end face of the wall of a pipe on which the protector is used, the improvement which comprises a side wall of increased diameter toward both ends and with a throat section intermediate the ends having a multi-convolution, continuous thread formed in the inner surface of the wall at the throat section for screwing over

the pipe threads that are to be protected, the seam at which the opposite edge of the metal meet being a butt seam and having a flush dovetail connection including a tab extending from one edge and engaged in a complementary groove in the opposite edge and with surfaces of the metal on opposite sides of the seam flush with one another and with a plurality of successive convolutions of the continuous helical thread extending across the flush seam at the dovetail connection, the outside surface of the protector over the threads being smooth and free of undulations from the threads, and the end flange merging with the side wall at a juncture where the diameter of the side wall is greater than at the throat sections, and in which the end flange is annular and extends radially inward and has an inside diameter substantially less than the inside diameter of the pipe on which the thread protector is intended to be used, and said end flange has undulations extending inwardly and located at widely spaced angular locations around the axis of the pipe and constituting the part of the end flange that contacts with the end face of the pipe, the inner edge of the end flange having notches therein, free of any obstruction longitudinally of the protector whereby a tool inserted in the notches can extend into the pipe on which the cap is screwed.

2. In a thread protector of the class wherein a single piece of metal is curved to bring its opposite longitudinal edges adjacent to one another and said edges are connected to form a generally cylindrical wall for surrounding the threads to be protected and in which a flange at one end of the piece of metal curves inwardly and extends across the end face of the wall of a pipe on which the protector is used, the improvement which comprises a side wall of increased diameter toward both ends and with a throat section intermediate the ends having a multi-convolution, continuous thread formed in the inner surface of the wall at the throat section for screwing over the pipe threads that are to be protected, the seam at which the opposite edge of the metal meet being a butt seam and the inside surface of the connector at the throat section having its threads extending across the seam, the end flange merging with the side wall at a juncture where the diameter of the side wall is greater than at the throat section, and the end flange having several corrugations of short circumferential extent and with large angular spacing from one another around the annular extent of the flange, the corrugations being displaced inwardly at locations where said corrugations contact with the end face of a pipe on which the protector is screwed, whereby the corrugations prevent the remainder of the flange from touching the end face of the pipe, and the total axial pressure component of the pressure between the pipe and connector threads is concentrated in the localized areas of contact of the flange corrugations with the end face of the pipe to provide resilient pressure for resisting rotation of the connector in a direction to unscrew it from the pipe.
